UNITED STATES PATENT OFFICE.

WILLIAM ALEXANDER MOSES, OF NEBRASKA, VIRGINIA.

RAILWAY-JOINT.

SPECIFICATION forming part of Letters Patent No. 393,481, dated November 27, 1888.

Application filed April 17, 1888. Serial No. 270,915. (No model.)

To all whom it may concern:

Be it known that I, WILLIAM ALEXANDER MOSES, a citizen of the United States, residing at Nebraska, in the county of Appomattox and 5 State of Virginia, have invented new and useful Improvements in Railway-Joints, of which the following is a specification.

The invention relates to improvements in railway-joints, its object being to strengthen 10 and brace the joint and give the meeting ends of the rails a firm support; and it consists in the construction and novel application of parts hereinafter described, illustrated in the accompanying drawings, and pointed out in the 15 claims hereto appended.

Figure 1 of the drawings represents a perspective view of a rail-joint having the invention attached thereto. Fig. 2 represents a 20 vertical longitudinal view of the joint. Fig. 3 is a perspective view of the angle-iron upon which the ends of the rails rest.

Referring to the drawings by letter, A A 25 designate the meeting ends of two rails resting on the cross-tie B and spiked to the ties on the sides thereof in the usual manner.

C C' are the adjacent cross-ties on each side of the tie B. The said ties C C' are provided with the transverse grooves c c', respectively, in their upper surfaces, which grooves are 30 situated immediately below the rails A.

D is an angle-iron having the ends d d', that lie in the grooves c c', respectively, and with 35 their upper surfaces flush with those of the ties C C', and secured to said ties by the pins d' passing through the openings d d' in the ends d d'. The openings d' are aligned with each other near one edge of the ends d d', and the openings d' are aligned with each other near the opposite edge, the openings d d' of 40 each end being situated at equal angular distances from each other. The angle-iron is provided on each side with the arms E, extending downwardly from the end portions, d d', and having their lower ends connected by the 45 bar F. When the parts are in position, the tie B rests upon the bar F with the arms E bearing against its vertical sides, so that the angle-iron connects and braces three ties together, the tie to which the rail-joint is connected being 50 the middle one of the three. The angle-

iron thus firmly supports and braces the rail-joint, extending the supporting surfaces to the adjacent ties and supporting the middle of the joint-tie at the under surface.

The device is strong, cheap, and durable, 55 and is obviously very efficient in use.

It should be observed that if the angle-iron D did not have its ends resting in grooves in the adjacent ties it could not be immediately below the rails, so as to be pressed upon and 60 held in place thereby.

It should also be observed that the parts or arms stand in and fill up the spaces between the ties, so that they are held thereby at their proper distances apart and cannot be pulled 65 together when the train passes over the joint.

Having described my invention, I claim—

1. In a rail-joint, an angle-iron supporting from below the cross tie to which the ends of the rails of the joint are attached, and having its horizontally-extended ends seated in grooves in the upper surfaces of the adjacent cross ties flush with said surfaces and immediately below the rails, substantially as specified. 70

2. In a rail-joint, an angle-iron supporting from below the cross-tie to which the ends of the rails of the joint are attached, having its extended ends secured to the upper surfaces of the adjacent ties, and with its arms or blocks E standing in and filling up the spaces between 80 said ties, substantially as and for the purpose specified. 75

3. In a rail-joint, the combination of the cross tie B, the cross-ties C C' adjacent thereto on each side, and provided, respectively, with 85 the transverse grooves c c' in their upper surfaces, and the angle-iron D, having the arms E, the cross-bar F, and the ends d d', respectively seated and secured in the grooves c c', with their surfaces flush with those of the cross-ties C C' and immediately below the rails forming 90 the joints, substantially as specified.

In testimony that I claim the foregoing as my own I have hereto affixed my signature in presence of two witnesses.

WILLIAM ALEXANDER MOSES.

Witnesses:

CH. H. SACKETT,
GEO. T. PEER.
